Inventor,
Addison H. Ames

UNITED STATES PATENT OFFICE.

ADDISON H. AMES, OF PHILADELPHIA, PENNSYLVANIA.

RAILWAY-TIE.

SPECIFICATION forming part of Letters Patent No. 391,999, dated October 30, 1888.

Application filed May 11, 1888. Serial No. 273,551. (No model.)

To all whom it may concern:

Be it known that I, ADDISON H. AMES, of Philadelphia, in the county of Philadelphia and State of Pennsylvania, have invented certain new and useful Improvements in Railway-Ties; and I do hereby declare the following to be a full, clear, and exact description of the invention, such as will enable others skilled in the art to which it appertains to make and use the same.

My invention relates to an improvement in railway-ties.

The object is to provide a strong, lasting, and comparatively inexpensive tie, which may be readily placed under the rails, which will prevent the track from spreading, will hold the rails securely in place, will tend to prevent the accumulation of water on the road-bed, will require but little ballast to hold it firmly in place, will cause no delay to the running of trains in repairing the track, and one, also, which may be easily manufactured at a very low initial cost.

With these ends in view my invention consists in certain features of construction and combinations of parts, as will be hereinafter fully described, and pointed out in the claims.

In the accompanying drawings, Figure 1 is a plan view of my improved tie. Fig. 2 is a longitudinal vertical section, and Fig. 3 is a transverse section through one of the triangular anchors.

A A' represent a pair of similar anchors constituting the opposite ends of the tie, and serving as an efficient means whereby the tie is compactly embedded in the ground or other material. These anchors are composed of metal, and consist simply of a triangular or V-shaped top, *a*, and integral rectangularly-spreading or outwardly-slanting sides *b*, the object of which construction is apparent, since the amount of ballasting necessary is diminished. Rigidly secured to the tops of these anchors, or formed integral therewith, if desired, are the metallic bars *C*, forming the body of the ties. The preferred dimensions of these bars is about eight and a half inches wide and three-fourths of an inch thick. Of course the length, width, and thickness will vary with the gage of the road and demands of service; but ordinarily about eight and a half feet in

length meets the demands. When not integral with the anchors, the bar is bolted or riveted to the tops of the anchors, with the smaller ends of the latter pointing toward each other 55 and about four feet apart.

Midway between the anchors a shoe, *D*, is rigidly secured to the under side of the body *C* of the tie. This may be a block of metal, and it is customary for it to be a V-shaped piece 60 of metal secured at each end to the bar.

A pair of chairs, *E*, are rigidly secured by bolts, rivets, or other means to the ties, at suitable intervals apart, one to lock upon the outer flange of one rail and upon the inner 65 flange of the other rail. Removable chairs *E'* are adapted to lock on the flanges of the rails opposite the fixed chairs, and the greater the weight on the rails the more the top of the rail inclines to the center of the track. 70

To place one of the ties in position, the removable chairs *E'* are taken off and the tie is inserted endwise beneath the rails and between adjacent ties until the fixed chairs are in position to bite upon the flanges of the rails. 75 The removable chairs are then placed in position and bolted on the ties. Ballasting is then tamped in the usual fashion about the anchors and the shoe and body of the tie.

From the construction, and particularly the 80 shape of parts and bearings, it is evident that neither an upward or endwise movement of the tie can possibly take place, as the rails are firmly held to the required gage, and, owing to the construction of the tie and bearings, the 85 spreading of the track is an impossibility.

From practical tests many advantages over other ties have been noted, and some of these are, to wit: the tie affords a permanent road-bed with the use of about one-half the ballast 90 required for other ties, which ballast may be of heavy or light material; no water can collect upon the track, and the construction of the tie and its bearings prevents the spreading of rails, the getting out of line of the track, and 95 the possibility of broken rails in cold weather.

It is evident that slight changes might be resorted to in the form and arrangement of the several parts described without departing from the spirit and scope of my invention; hence I 100 do not wish to limit myself to the particular construction herein set forth; but,

Having fully described my invention, what I claim as new, and desire to secure by Letters Patent, is—

1. The combination, with the anchors consisting of the flat triangular-shaped plates having outwardly-inclined depending flanges, of the body connecting the top plates of the anchors and a shoe attached to the lower side of the body.
- 10 2. The combination, with the body of a tie, a V-shaped anchor secured to the ends of said body, said anchors having spreading rectangu-

lar sides, and a V-shaped shoe secured to the lower side of the tie midway between the anchors, of fixed and removable chairs connected 15 with the tie, substantially as set forth.

In testimony whereof I have signed this specification in the presence of two subscribing witnesses.

ADDISON H. AMES.
